DISTILLATION OF TAR OR PITCH AND APPARATUS THEREFOR

Stuart Parmelee Miller, Englewood, N. J., assignor to The Barrett Company, New York, N. Y., a corporation of New Jersey

Application August 9, 1929. Serial No. 384,665

11 Claims. (Cl. 202—30)

This invention relates to improvements in the distillation of tar or pitch and the production of coke therefrom.

According to the present invention, the tar or pitch to be distilled is brought into intimate and direct contact with hot gases, for example hot coal distillation gases or other hot coal gasification gases at a sufficiently high temperature to distill the tar or pitch and remove substantially all of the oil constituents therefrom and to leave a coke residue, and the oils distilled from the tar or pitch are removed with the gases employed for the distillation and are subsequently condensed therefrom.

It has been proposed to distill tar or pitch to produce coke in externally heated stills, but such distillation, when carried out by the commonly known methods, is accompanied by a considerable decomposition of oil constituents of the tar or pitch distilled, with corresponding reduction in the yield of distillate oils, and increase in the coke residue. Particularly at the higher temperatures required for the distillation of pitch to produce coke, the decomposition of heavy distillable constituents, such as resins, greases, etc., is very considerable, but even at lower temperatures appreciable decomposition of distillable oils takes place when the distillation is carried out in externally heated stills of the commonly known types.

The present invention provides an improved process in which a materially increased yield of distillate is obtained from a tar or pitch, and in which objectionable decomposition of distillable constituents is reduced to a minimum.

The word "tar" in the following includes raw tar containing a certain percentage of water, dehydrated tar partly or entirely freed of water, and stripped tar from which a part of the more volatile constituents have been removed. The word "pitch" refers to the distillation residues of tar.

According to the present invention, I provide a still into which the tar or pitch to be distilled is introduced, and I heat the tar or pitch and effect its distillation by introducing into the still, and into direct and intimate contact with the tar or pitch therein, hot gases at a sufficiently high temperature to effect distillation of the tar or pitch and the production of coke therefrom. The production of coke from pitch by this method is in part the result of volatilization of pitch components and in part the result of thermal decomposition of pitch components to form a carbonaceous residue. The distillate oils are taken off in vapor form with the gases and the mixed gases and vapors are cooled to condense the distillate. The present process is advantageously carried out in a continuous manner, with continuous introduction of tar or pitch to be distilled, and with continuous production and discharge of coke from

the apparatus, as well as continuous withdrawal and condensation of distillate.

The distillation of the tar or pitch, according to the present process, may be carried out at coal distillation plants, and with the use of hot coal distillation gases, such as the gases from the ovens of a coke oven plant. The coke oven gases leave the individual ovens at a high temperature around 600° to 700° C. or higher. I make use of such gases by collecting them and passing them while still at a high temperature into the still and into contact with the tar or pitch to be distilled. By withdrawing the gases from individual ovens through insulated lines and preventing the cooling of the gases before they reach the still, they can be employed at practically their maximum temperature for the distillation and coking operation. In the case of a coke oven plant, the coking still can be located on top of the block, or at one end of the block, and with an insulated pipe leading the gases from a sufficient number of the individual ovens to the coking still for carrying out the distillation and the coking operation. Or, instead of collecting the gases from several ovens and then passing the combined gases into the still, the gases from individual ovens may be passed directly into the still and at different parts of the still.

The present process can be carried out with coke oven or other tar, introducing the tar into the still, and carrying out the distillation in a single operation. In this case, the entire distillate will be carried off from the coking still with the gases. Instead of distilling tar, the tar may be separately distilled to produce pitch, and the pitch subjected to further distillation and coking according to the present process. In such case, the pitch is charged into the coking still and is subjected to distillation by direct contact with the hot gases.

A particularly valuable application of the invention involves the distillation of tar in two stages, in the first of which it is subjected to distillation by direct contact with hot coal distillation gases to produce a pitch of medium or of high melting point, for example a pitch of around 300° F. or 400° F. melting point, and the resulting pitch is then subjected to further distillation in a coking still by direct contact with hot coal distillation gases to produce coke and additional distillate. In such a two stage distillation, the distillate from the two stages can if desired be separately condensed. The distillate from the coking still, when high melting point pitch is charged into it, will be an unusually heavy distillate which, when cold, will be solid or semi-solid in character. In condensing such a heavy distillate, care should be taken to avoid cooling to too low a temperature such as would solidify the

condensed heavy distillate. A hot condenser maintained at a sufficiently high temperature to keep the condensate thinly fluid, can advantageously be employed, or a condenser in which 5 lighter oils are simultaneously condensed to dissolve and dilute the heavy condensate and prevent it from separating in a solid condition.

The coking of pitch by direct contact with hot coal distillation gases which effect the heating 10 of the pitch and the distillation of oils and resins, etc. therefrom is particularly advantageous because the excessive heating in ordinary coke stills is avoided, the large amount of inert gases allow reduction of the temperature at which 15 the heavy distillate is removed from the still, and, as a result, an unusually high yield of distillate can be obtained. Whereas, by ordinary methods of distillation, yields of distillate oils of around 50 to 60% or somewhat more are obtained on the 20 distillation of tar to coke, the improved process of the present invention enables a yield of as high as 80 or 90% of the tar to be obtained in the form of valuable distillates, with corresponding reduction in the amount of coke produced.

25 During the coking of the pitch residue decomposition of the non-volatile pitch constituents and of some of the very high boiling volatile constituents goes on. Fixed gases are generated. They are of value as fuel gases. When 30 coke oven gases or other gases which are to be subsequently employed as fuel gases, are used for converting pitch to coke according to this invention, the fixed gases generated during the conversion blend with the coke oven gases, etc. 35 and are valuable products of my process.

The coking still employed in the present process is advantageously one in which the tar or pitch is kept agitated and in which the coke as it is being formed is kept agitated and in 40 which the operation is carried out continuously so that the coke is continuously discharged in a broken up or finely divided condition from the apparatus. An apparatus provided with rotating or reciprocating stirrers or agitators or 45 scrapers can be employed, which will keep the tar or pitch agitated and which, as the pitch gradually changes to coke, will keep the semi-coke or coke agitated and expose fresh surfaces thereof to contact with the hot gases. A rotating 50 cylindrical vessel can also be employed into one end of which the tar or pitch to be distilled is introduced, and from the other end of which the coke is discharged, and through which the hot coal distillation gases pass countercurrent to 55 the pitch and coke. In such a rotating still, the prevention of the formation of a solid layer of coke can be effected by providing agitating elements or tumblers which serve to break up the coke and maintain it in a loose or divided form 60 such that it can discharge from the apparatus.

The coke produced by the present process is a valuable fuel product.

The distillate obtained by the present process will vary with the character of the material distilled. Where tar is distilled and the distillation 65 carried to completion in a single still, the entire distillate will be obtained as vapors admixed with the gases employed for the distillation, and, on cooling such gases and vapors, the total distillate can be condensed together, or fractionally condensed to give a plurality of products. Any tar constituents carried by the gases employed for 70 the distillation will be to some extent separated from the gases in the still but to a considerable extent will remain in the gases leaving the still.

On cooling these gases, any tar or pitch constituents which they contain will be separated with the condensate from the distillation. The gases employed for the distillation may be hot coal distillation gases which contain tarry or pitchy constituents such as hot coke oven gases or gas retort gases or coal gasification gases such as hot carburetted water gas, or hot coal gasification gases substantially free from such entrained impurities, such as hot water gas, for example 80 may be employed.

When the distillation is carried out in two stages, the distillate from the first stage, in which tar is distilled to produce pitch, can be kept 85 separate and recovered as a creosote oil, or fractionally condensed to give a heavier creosote oil and a lighter carbolic oil, etc. If the gases employed for the distillation of the tar to produce pitch contain tar or pitch constituents and the distillation is carried out with thorough scrubbing of the gases, the distillate will be a relatively 90 clean oil, that is, free or substantially so from entrained impurities.

The distillate from the coking still, when pitch is supplied to it, will be a heavy distillate, and 100 care should be taken to condense it at temperatures which will keep it fluid until it is removed from the condensers. Where gases, such as hot coke oven gases, which contain entrained tarry and pitchy constituents, are employed for coking the pitch, the distillate obtained will comprise tarry and pitchy constituents which will 105 separate from the gases on cooling. Where a clean distillate is desired direct, the gases and vapors leaving the coking still may be cleaned 110 at a high temperature in any manner adapted to the removal of tarry and pitchy particles from such high temperature gases. On cooling these cleaned gases clean distillate will be obtained.

The heavy distillate from the coking still can 115 be fractionally condensed to recover a heavy distillate of a semi-solid or solid character, or this heavy distillate can be condensed in admixture with lighter oils and recovered as a composite 120 liquid product made up in part of the heavy distillate and in part of lighter oils. Where two successive stills are employed for two stage distillation of the tar, first to produce pitch and second to coke the pitch, the total distillate from both stills can be combined together to give a 125 composite total distillate which may represent as high as 80 or 90% of the tar distilled. Where gases containing entrained tarry and pitchy 130 particles are employed for the distillation, and a combined clean oil distillate from both stages is 135 desired, the gases and vapors from the coking still may advantageously be passed through the still of the first stage where tar is distilled to pitch, and by intimate and intensive spraying of the gases and vapors in this still with the tar, the 140 gases will be detarred and the tar will be distilled to pitch. When this is done part of the least volatile constituents may be reabsorbed by the pitch in the still of the first stage, and thus be conveyed back to the coking still. In this cycle 145 such constituents may in part be decomposed and coked. On subsequent cooling of the detarred gases, a clean total distillate will be obtained. Instead of condensing a total distillate, the distillate can be fractionally condensed and selected 150 fractions employed for creosoting or other purposes.

The invention will be further described in connection with the accompanying drawings which illustrate in a somewhat conventional and dia- 155

grammatic manner, suitable apparatus for carrying out the improved process.

Fig. 1 shows a plan view, schematic in part and with part broken away, of a coke oven plant 5 equipped with means for the continuous distillation of tar to coke in two stages, viz. distillation of the tar to pitch and then distillation of the pitch to coke, by hot coal distillation gases;

Fig. 2 is an elevation in section of one form of 10 the coking still, tar still and coke receiver of Fig. 1;

Fig. 3 is a vertical section of the coke still on the line 3—3 of Fig. 2;

Fig. 4 is a vertical section of the tar still on the 15 line 4—4 of Fig. 2;

Fig. 5 is a vertical section of the hot condenser;

Fig. 6 shows a plan view, schematic in part and with part broken away, of a coke oven battery 20 equipped with different means for the distillation of tar to coke in two stages, by hot coal distillation gases;

Fig. 7 is a longitudinal section of the coke still of Fig. 6; and

Fig. 8 is a section of the tar still on the line 25 8—8 of Fig. 6.

The arrangement of the tar still and coke still shown in the drawings may be applied to a coke oven battery or to other coal carbonization or gasification plants, such as gas producer plants. 30 gas retort plants, water gas plants, etc., with appropriate modifications.

Fig. 1 shows means for distilling tar to coke by hot coke oven gases with countercurrent flow of the gases and the material being distilled. The coke oven battery 5 is shown as being equipped with uptake pipes 6, through which the coke oven gases pass from the ovens to the collector main 7, whence they pass through the center-box 8 through the cross-over main 9 to condensers, etc. 40 This may be the usual type of apparatus and is shown schematically.

At the rear of the battery additional uptake pipes 10 are provided on selected ovens through which the gases from these ovens may be directed 45 by the manipulation of valves in the uptake pipes 6 and 10 into the coking still 11. Pitch from any suitable source, preferably in a fluid condition, is fed to the coke still through the opening 12. In Fig. 1 the pitch is shown as coming directly and 50 continuously from the tar still 13, from which it is drawn off through a suitable draw-off 14.

The coke still is equipped with agitating means adapted to keep the pitch and the coke produced therefrom in motion during its passage through 55 the still. For this purpose the still 11 is equipped with arms 15, provided with scraping shoes 16 and baffles 17 which serve to prevent the building up of pitch or semi-coke on the arms, scrapers and retort walls. Suitable mechanism 18 is provided for transmitting an oscillatory motion to the arms through the shaft 19.

The hot gases from selected ovens passing up through the uptakes 10 carry the hot gases from the selected ovens into the still, cause distillation 60 of volatile constituents therefrom, remove the vapors from the proximity of the material being distilled and flush these vapors from the still. The gases from one or more ovens may advantageously be admitted to the end of the still as at 20 to prevent the formation of "pockets" of vapor at the end of the still and to ensure thorough flushing of the vapors from the end of the still.

The pitch which enters the still at 12 is distilled 70 by the hot gases in its passage through the still and is discharged from the still through the chute

21 as coke. The revolving gate 24 is provided to control the rate of discharge from the chute 21. The hot coke is advantageously quenched in water as it leaves the still. For this purpose the tank 22 containing sufficient water to seal the end 80 of the chute is provided. An endless conveyor 23 is also provided for removing the quenched coke from the tank 22 to a storage bin 25.

Other means for collecting and removing the coke may be employed. The coke, may, for example, be collected in a hopper sealed against loss of gas to the atmosphere. The coke may, by manipulation of suitable gates, be periodically removed.

Coal distillation gases, such as coke oven gases, etc., contain particles of coke and pitchy particles, etc., known as "tar fog" which persist, at least to some extent, in the gases, even though the gases are passed through condensers or scrubbers of the ordinary type. The gases leaving the still 11 will ordinarily contain much of the "tar fog" present in the gases as they enter the still from the ovens. In addition these gases leaving the still contain oil vapors present in the gases leaving the ovens and also vapors distilled from the pitch in the still 11, as well as ammonia, etc., ordinarily present in coke oven gases. The vapors distilled from the pitch comprise vapors of high boiling resinous and greasy materials which are solid or semi-solid at ordinary temperatures in an isolated state. By fractionally cooling the gases these resinous and greasy substances may be recovered as a separate fraction. However, if the gases are cooled as they leave the still 11, the condensate or condensates produced will be contaminated by entrained solid and liquid impurities present in the gases leaving the ovens as "tar fog", and possibly by some particles of pitch or coke carried over by the gases from the still 11. Although the gases may be cooled directly 100 after they leave the still, and by fractional cooling using a suitable condenser, such as a hot condenser, a heavy resinous substance, as well as light and heavy tarry oils comprising creosote constituents and carbolic oil constituents, or one 105 total tarry oil or different tarry oil fractions may be obtained, the gases leaving the coke still are advantageously cleaned before being cooled, and the cleaning is advantageously done at a high 110 temperature. Any suitable means for cleaning 115 may be employed such as an electrical precipitator, a hot gas scrubber, etc.

In the drawings, means is shown for bringing the hot gases into contact with an intensive, 120 finely divided spray of hot tar or pitch which detars the gases, removing substantially all entrained particles therefrom. In the drawings the detarring is done in the tar still. The hot gases are brought from the coke still 11 to the tar still 125 13 through the short main 27. This main is heavily insulated as at 28, and each piece of the equipment between the ovens and the hot condenser may advantageously be similarly insulated. 130

In the still 13 the gases are brought into contact with tar or partially distilled tar or pitch, which is distilled by the gases, and which, in turn, by intimate contact with the gases, detars them. The tar is advantageously admitted to the still 145 through sprays 29 in the settling tower 30. The tar may if desired be preheated in any suitable way. This preheating of the tar increases the unit capacity of the hot gases to distill tar and to coke pitch. The higher the temperature to 150

which the tar is preheated the smaller the quantity of hot gas required.

In the drawings, a roll 31 which dips to only a slight extent into the tar or pitch, located at one side of the still 13 and rapidly rotated by the motor 32, is provided for effecting the intensive spraying of the gases necessary to detar them and at the same time to flush the walls of the distilling main to prevent accumulation of coke.

10 Any spray of tar or pitch carried from the still 13 by the gases is removed by the baffles 34 and the tar sprayed from 29, and returns to the still 13.

The flow of material through the tar still and then through the coke still, the quantity of gases passed through the stills, the temperature to which the tar is preheated before entering the sprays 29, etc., are so regulated and the apparatus is so designed that the tar is distilled in the still 13 to pitch of a melting point just less than

20 that which might cause difficulties to arise due to coking of the pitch to an undesirable degree in the tar still, e. g., a melting point over 300° F. and even up to 350° F., and preferably not much higher. Where desirable, a portion of the pitch 25 from the still may be drawn off through the draw-off 33', solidified, as by chilling with cold water from 34' and conducting away in gutter 35', and used for any desired purpose.

The detarred gases leaving the settling tower 30 through the main 35 carry vapors distilled from the tar in its conversion to coke. These vapors comprise constituents of lower and medium boiling points such as light oils, carbolic oil constituents, cresote oil constituents, and anthracene oil constituents as well as high boiling constituents of a resinous or pitchy character. The vapors may be condensed in one step to produce a total condensate, or they may be cooled in two or more steps.

40 The high boiling resinous or pitchy substances carried as vapors in the gases may be obtained as a separate fraction by passing the gases through a hot condenser in which the temperature of the gases is reduced to the extent necessary to condense the desired high boiling constituents, but not sufficiently low to condense other oils which it is desired to carry over with the gases into the other condensers, and not sufficiently low to cause solidification or hardening of the high boiling resinous substances to such an extent as to cause clogging of the tubes of the condenser or the draw-off for these substances. The draw-off from the condenser may advantageously be steam-jacketed or at least heavily insulated.

50 Although other condensing means may be employed, in the drawings the gases are shown as passing first through the hot condenser 36, which is shown as an indirect condenser, then through another indirect condenser 37 for removing other and somewhat lower boiling constituents, then through the direct condenser 38 where lower boiling constituents are removed and then through the exhauster 39. From the exhauster the gases are advantageously passed to means (not shown) 65 for removing ammonia, light oils, etc., which may advantageously be accomplished in the means used for recovering these constituents from the gases passing through the cross-over main 9 to the ordinary by-product recovery apparatus.

70 The drawings show the condensers 36 and 37 as comprised in one condenser tower. The gases enter at the bottom of the tower and pass up through the hot condenser 36 which is here shown as of the indirect type in which the gases pass up 75 through the tubes 40 which are surrounded by a

cooling medium of regulated temperature which may for example be a heated gas, or a fluid such as steam, which passes into the jacket through 42 and out at 41. Hot high boiling oil may be circulated through the condenser for removal of heat and may then be passed to a suitable heat interchanger for cooling before return to the condenser.

80 Cooling of the condenser may also be accomplished by supplying to it in regulated amount 85 a liquid which will be vaporized in the condenser and hence will remove heat as latent heat. The vapors may be conducted away, be condensed and the condensate be returned for further vaporization and heat removal. The resinous materials which are condensed are withdrawn through the insulated draw-off 43 and collected in 44.

90 The gases then pass up through the gas passage 45 into the condenser 37 where high boiling oils are condensed and drawn off through 46 to the storage receptacle 47.

95 From this condenser the gases pass through the main 48 to the condensers 38 which are of the ordinary direct type in which the gases are cooled 100 with sprays of water or ammonia liquor. The clean lower boiling oils may be here collected as a single fraction comprising the carbolic oils, or two separate fractions may be collected. Where one fraction is collected the liquor from these 105 condensers may be drawn to the decanter 49 and from thence the clean oils may be drawn off into the receiver 50.

110 Fig. 6 shows different means for distilling tar to pitch by a two-stage process. Hot coke oven 115 gases are admitted at one end of the coking still 58 and pitch is admitted at the other. The pitch and the hot gases flow through the still countercurrent to one another. The gases leaving the coking still are detarred in the tar still 60 and the 120 tar is distilled. The flow of tar and gases in this still 60 is concurrent. The hot gases are brought in direct contact with the fresh tar, and the finished pitch leaves the still in contact with the vapor laden and somewhat cooled gases which 125 have been employed for the distillation. As the finished pitch is not brought into contact with the hottest gases, the pitch may be distilled to a melting point of 350° F., or 400° F. or higher without objectionable coking in the tar still.

130 In Fig. 6 a coke oven battery 5 with uptake pipes 6, collector main 7, center-box 8, and cross-over main 9 are illustrated schematically as in Fig. 1. Uptake pipes 51 situated at the rear of the battery are connected with a hot gas header 130 52 which collects the fresh hot gases from a number of ovens and introduces them into one end of the coking still through the opening 53. The ovens connected with the hot gas header through the uptake pipes 51 are also connected with the 135 collector main 7 by means of uptake pipes 6. By properly regulating valves in the uptake pipes 6 and the uptake pipes 51, the gases from these ovens may be directed either to the collector main 7 or to the hot gas header 52. The hot gases in 140 passing through the still pass countercurrent to the pitch which is admitted to the still through the opening 54 and the pitch is kept in constant motion by the oscillating arms 55 which are similar to the arms 15 described in connection with 145 the coke still 11 in Fig. 1. The coke is withdrawn from the coke still through the chute 56, cooled in the tank 57, and removed by an elevator similar to that shown in connection with tank 22 of Fig. 1.

The hot coke oven gases enriched in condensable constituents leave the coke still 58 through the main 59 and are passed through the tar still 60 in which the hot gases are sprayed to remove 5 entrained "tar fog", etc. The gases leaving the coke still may be sent directly to condensers or may be cleaned in any suitable manner and then condensed. By passing the hot gases through the tar still 60, and detarring them therein by 10 an intensive tar spray, the gases are detarred and the tar is distilled. The pitch produced is withdrawn from the still through the draw-off 61 and all or a part of the pitch may advantageously be directed into the coke still 58 where the pitch 15 will be converted to coke, although it is to be understood that the coke still 58 may be utilized for treating pitch from another source than the tar still 60. A portion of the pitch produced may be drawn off through 61', cooled with water from 20 62' and stored in 63'.

20   62 and stored in 63. The tar still in the drawings is shown as equipped with a roll 62 which is adapted to be rotated at high speed by the motor 63. By situating the roll so that it dips to only a slight extent into the tar or pitch which may be fed to the still through the pipe 64, the tar or pitch is sprayed up into the gases, the tar still is filled with a fine spray of tar or pitch thrown from the roll, and the walls of the still are continuously 25 washed with a moving layer of tar or pitch. This spray detars the gases and the tar which may advantageously be preheated before entering the still is distilled by the direct contact between the tar and the gases. Additional hot coke oven 30 gases may be admitted to the tar still through one or more uptake pipes 65 in order to maintain the temperature of the gases within the tar still above the dew point of the constituents which it 35 is desired to drive over from the tar still into the condenser 66, although it will in general be more desirable to add such gases through the hot gas header 52 in order that they may be employed 40 at maximum temperature for coking the pitch.

45 at maximum temperature for carrying the pitch.
The hot gases coming from the coke still pass through the tar still where they are detarred and further enriched in condensable constituents. These gases are passed up through the settling tower 67 situated on top of the tar still and entrained particles of pitch carried from the still by the gases will settle out of the gases in this settling tower and return to the pitch within the still. The gases which are substantially free from entrained particles pass through the main 68 to the condenser 66. The main 59 and the other elements of the apparatus which the gases pass through in travelling from the uptake pipes 51 to the condenser 66 may advantageously be heavily insulated to prevent cooling of the gases and possible condensation of oil constituents from 60 the gases.

66 Although the Fig. 6 shows one condenser for
cooling the gases to recover the oils carried by
the gases, it is to be understood that fractional
condensing means may be employed. The liquid
65 collecting in the bottom of the condenser 66 is
drawn off into the decanter 67'. From the de-
canter the clean oils are separated into the stor-
age tank 68'. From the condenser the gases pass
through the exhauster 69 to means for recover-
70 ing ammonia, light oils, etc.

By bringing the tar into intimate contact with the hot distillation gases in still 60 in the form of an intensive spray, and distilling the tar to pitch with a melting point of around 400° F., a yield of around 70 to 75% of clean oil distill-

ate may be obtained. By coking this pitch with the hot gases in the coke still 58, and agitating the pitch in the still, and the coke as it is formed, and vaporizing the volatile constituents and flushing them from the still as they are formed, an additional distillate of up to 5% or even as much as 15% will be obtained. 80

In the drawings the invention is described more particularly as applied to distillation with hot coke oven gases. It is to be understood that other hot gases, such as hot retort gases, hot water gas, hot producer gas, flue gases, super-heated steam, etc. may be employed. After the gases employed for the distillation have been cooled for the separation of oils, they may be reheated and be used for further distillation where desired. Where the distillation to coke is effected by hot water gas, steam or another gas which is free from or low in entrained impurities, the resulting gases on cooling will yield directly distillates which are free from or low in tar or pitchy constituents without first being subjected to a cleaning treatment. Tar may be distilled to coke, or pitch which may be pitch produced as a part of the same operation by distillation of tar in hot coke oven gases or other hot gases or pitch from another source produced in the usual way may be distilled to coke.

Figs. 1 and 6 show coke stills from which the hot gases pass to tar stills in which tar is distilled to pitch which may then be fed to the coke stills, and in which the gases are detarred and enriched with lighter oils. Clean oil fractions or total distillates may be recovered from the enriched gases by condensation. Tar may be distilled and coke produced in the coke still only. In this case tar will be fed direct to the coke still. It will be distilled by the hot gases, but where gases containing tarry or pitchy constituents are employed for the distillation the distillate obtained will contain tarry or pitchy matter since the hot gases will not be cleaned to the same degree as when they pass through tar stills such as illustrated in Figs. 1 and 6. The gases will be enriched by the oil vapors resulting from the distillation. Where a gas containing tarry or pitchy constituents is employed for the distillation, if the tar fed to the still is sufficiently preheated the gases may be so enriched as to yield on cooling distillates sufficiently low in free carbon to allow their use as distillate oil for creosoting. Where tarry oils of low free carbon content are desired for use as creosoting compositions, either the gases may be enriched to a less degree, or the gases may be enriched to a greater degree and tar may be blended with the resulting relatively clean oils to yield the desired creosoting composition.

The process and apparatus described provide for distilling tar or pitch in hot gases, e. g. hot coke oven gases at substantially the temperature at which they leave the ovens for the production of coke, high yields of distillate oils, and valuable fuel gases where hot coal distillation or coal gasification gases are employed. 140

The coke produced by my process is a high grade coke, high in carbon content and low in ash, e. g. containing usually not over 1 to 2% ash, and in many cases not over $\frac{1}{2}$ to 1% ash. It is produced continuously and may be produced in crushed or nodular form which may readily be prepared for sale by screening. If the operation is conducted in a rotating retort with tumblers, e. g. balls or rods, finely crushed coke may readily be produced. It ordinarily will

not require crushing unless it be desired to employ or market it all in relatively small sizes. The volatile content of the coke may be regulated within wide limits by regulating the quantity of the hot gases passed through the still. Cokes of varying degrees of combustibility may thus readily be produced for the special purposes to which such high grade materials are put.

I claim:—

10. 1. The method of distilling tar and producing coke, gas, and distillate oils therefrom, which comprises subjecting the tar to distillation by spraying it into hot coal gasification gases and then further distilling and decomposing the tar distillation residue by direct contact with hot coal gasification gases thereby producing coke, and cooling the gases and vapors resulting from the distillation to recover distillates therefrom.
15. 2. The continuous method of converting pitch to coke, which comprises heating the pitch by direct contact with hot coal gasification gases at a sufficiently high temperature to remove distillates from the pitch thereby producing coke, gradually supplying pitch for conversion to coke, stirring or agitating the pitch during the conversion, and continuously discharging coke from the coking chamber.
20. 3. The method of distilling tar to pitch and then converting pitch to coke, which comprises bringing the pitch into direct contact with hot coal gasification gases in a still thereby converting the pitch to coke, stirring or agitating the pitch during the conversion, spraying the tar into the hot gases and vapors resulting from the production of the coke to distill the tar to form the pitch, drawing off the pitch from the tar distillation and feeding it to the still in which the coke is produced.
25. 4. The method of distilling tar to pitch and then converting the pitch to coke in hot coal distillation gases, which comprises bringing the pitch into direct contact with the hot coal distillation gases to distill the pitch and produce coke therefrom, and then spraying the tar into direct and intimate contact with the resulting gases and vapors whereby the tar is distilled to produce the pitch and entrained impurities are removed from the gases and vapors, and thereafter cooling the gases and vapors to separate clean distillate therefrom.
30. 5. The continuous method of converting pitch to coke, which comprises supplying the pitch gradually to one end of an elongated still, causing the pitch to flow progressively through the still from one end to the other while agitating or tumbling it, introducing hot coal gasification gases into the other end of the still and causing them to flow through the still countercurrent to the flow of the pitch, whereby oils are progressively distilled from the pitch and the pitch is converted into coke, stirring or agitating the pitch during the conversion, and continuously discharging the coke from the still.
35. 6. The improved process of distilling tar and of producing distillate oils and coke therefrom, which comprises subjecting the tar to distillation in a plurality of stages, in one stage bringing the tar into direct and intimate contact with hot coal gasification gases to distill the greater part of the oil content from the tar and in the other stage continuing the distillation of the distillation residue from the first stage and converting it to coke by bringing it into direct contact with other hot gases, simultaneously producing gas and ad-

ditional distillate, and cooling the gases respectively employed for the distillation of the tar and residue to condense distillates therefrom.

7. Apparatus for the distillation of tar and the production of coke and distillate oils therefrom comprising two stills, one for the distillation of tar to produce pitch, and the other for the conversion of pitch to coke, means for passing hot gases through each of said stills in direct contact with the tar or pitch contained therein, means for supplying tar to one of said stills, means for withdrawing pitch from said still and introducing it to the second of said stills, means for withdrawing coke from the second of said stills, and means for withdrawing from each of said stills the admixed gases and vapors and for cooling the same to condense oils therefrom.

8. Apparatus for the distillation of tar and the production of coke, gas and clean distillate oils therefrom comprising a source of hot coal gasification gases, means for bringing partially distilled tar or pitch into direct and intimate contact with the hot gases at a sufficiently high temperature to distill volatile constituents therefrom and produce coke, means for bringing tar into direct contact with the resulting gases and vapors in the form of an intensive spray to detar the gases and vapors and simultaneously distill the tar to produce said partially distilled tar or pitch, and condensing means for cooling the detarred gases and vapors to produce distillate oils therefrom.

9. Apparatus for the distillation of tar and the production of coke, gas and distillate oils therefrom comprising two stills, means for passing hot gases into the first still, means to supply distillation residue from the second still to the first still, means for continuously discharging coke from the first still, a main to pass gases and vapors from the first still to the second still, a tar feed to the second still, and means in the second still for producing an intense spray of tar in the gases passing therethrough.

10. The process of distilling tar and producing distillate oils and coke therefrom, which comprises bringing the tar into direct and intimate contact with hot coal gasification gases to distill off oil from the tar and produce a pitch residue and distillate oil vapors, bringing the pitch residue into direct contact with hot coal gasification gases so as to coke the pitch residue and produce gas and distillate oil vapors, withdrawing the hot gases and distillate oil vapors from the tar distillation step, withdrawing hot gases and distillate oil vapors from the coking step, and cooling the gases and vapors to condense distillate oils therefrom.

11. The process of distilling tar and producing distillate oil and coke therefrom, which comprises bringing the tar into direct and intimate contact with a mixture of hot coal gasification gases, gas, and distillate oil vapors in a tar still to distill oils from the tar and produce a pitch residue, bringing the pitch residue into direct contact with hot coal gasification gases so as to coke the residue and produce gas and distillate oil vapors, withdrawing the resultant mixture of coal gasification gases, gas, and distillate oil vapors and bringing it into contact with tar in the tar still, withdrawing the hot gases and vapors from the tar still, and cooling them to condense distillate oils.
